UNITED STATES PATENT OFFICE.

AXEL OSVALD APPELBERG, OF STOCKHOLM, SWEDEN, ASSIGNOR TO AKTIEBOLAGET BIRKA REGULATOR, OF STOCKHOLM, SWEDEN.

THERMOSTATIC SWITCH.

Application filed January 20, 1923. Serial No. 613,920.

To all whom it may concern:

Be it known that AXEL OSVALD APPELBERG, a subject of the King of Sweden, residing at 11 Roslagsgatan, Stockholm, Sweden, has invented certain new and useful Improvements in Thermostatic Switches, of which the following is a specification.

The invention relates to thermostatic switches of the kind which are disposed in hermetically closed glass receptacles for the purpose of protecting the break contact of the switch, and the main object of the invention is to facilitate the manufacturing of such thermostatic switches.

15 The invention consists in the construction and novel combination and the arrangement of parts as well as the method of manufacturing hereinafter fully described, illustrated in the accompanying drawing and set forth in the claims hereunto appended.

In the drawings:

Figs. 1, 2 and 3 are three different views of the thermostatic switch the glass receptacle being shown in section.

Fig. 4 shows the base of the receptacle with the connecting terminals, mounted thereon.

Fig. 5 shows the insulating stud whereby the switch is secured to the connecting terminals.

Fig. 6 shows the switch detached from the base.

The switch consists of two contact arms 35 1, 2 and a thermostatic element 3 fastened to the contact arm 1 by a rivet 4. The contact arm last mentioned consists of a thin plate spring carrying at its outer end a contact plate 5. Riveted to said plate 5 is one 40 of the two contact pins 6, 7 forming the break contact of the switch. Said contact pins preferably consist of tungsten or other refractory metal. The contact arm 2 carrying the other contact pin 7 consists of a 45 strip of metal which is relatively stiff.

The two contact arms 1 and 2 are firmly connected with one another by means of an insulating stud 8 and a screw 9 passed through a central hole of the stud and provided with a nut 10. Interposed between the head of the screw 9 and the contact arm

1 and between the nut 10 and the contact arm 2 are washers 11 and 12 respectively of insulating material, f. i. mica. The contact arms 1, 2 are extended beyond the connection 8, 9 and connected at their outer ends by means of a similar connecting device comprising an insulating stud 13, a screw 14, a nut 15 and insulating washers 16, 17. By the connection last mentioned the contact 60 arms are also secured to two corresponding terminal plates 18, 19 and thereby rigidly connected with the base or bottom 20 of the tubular glass receptacle 21, the terminals 18, 19 being sealed in the base 20 and electrically 65 connected with the outer conductors 22, 23. Instead of the screws 9, 14 rivets may, evidently, be used to keep the parts together.

The thermostatic element 3 consists of a bimetallic strip secured in place by the connecting device 8, 9. It is adapted to be bent, upon an increase of temperature, towards the contact arm 1 and to operate said contact arm so as to open the contact 6, 7 at a certain temperature. The receptacle 21 may 75 be either evacuated or filled with an inert gas.

The object of constructing the switch in the way described is to facilitate the manufacturing and adjustment of the switch. 80 Heretofore, in the manufacture of such switches the contact arms have usually been sealed directly into the glass base, the switch being then adjusted and fastened in the receptacle by sealing the base onto one end of 85 the receptacle. This method, however, has the disadvantage that the contact arms may easily be brought out of their adjusted position, when the switch is being inserted in the receptacle. Such disadvantage is now 90 removed according to the present invention by the switch being made up of two different parts, one of which consists of the switch member shown in Fig. 6, while the other part consists of the glass base 20, shown in 95 Fig. 4, together with the contact terminals 18, 19 mounted thereon. The said two parts may, consequently, be manufactured separately independent of one another. As will appear from Fig. 6, the contact arms 1, 2 100 and the thermostatic element 3 may thus be rigidly connected with one another by means

of the connecting device 8, 9 so as to make it possible to adjust the switch properly before it is secured to the glass base. Such an adjustment may for instance be effected by bending the spring 1 and by setting a screw 24 provided at the outer end of the bimetallic strip 3, said screw being accessible through an aperture 25 in the contact arm 2. After the switch member and the glass base 20 with its contact terminals having been thus manufactured separately the two parts are connected together as shown in Fig. 2 by means of the insulating stud 13 and the screw 14, the fork-shaped ends of the contact terminals 18, 19 being clamped between the insulating stud and the contact arms. In this way the terminals are connected at the same time electrically with the contact arms. The switch is then introduced into the tube 21, wherein it is fixed in place by sealing the glass base 20 onto one end of the tube. Finally, the tube is evacuated or filled with gas and closed up similarly as ordinary electrical incandescent lamps.

25 The thermostatic switch shown in the drawing is adapted to be placed directly in thermal connection with the source of heat to be controlled, but, evidently the switch may be operated indirectly by means of heating resistance placed around or inside the receptacle or on the thermostatic element.

I claim:

1. In a thermostatic switch disposed in a closed receptacle the combination of a contact device, a number of connecting terminals attached to the base of the receptacle and means for connecting said contact device and said terminals mechanically and electrically.
2. In a thermostatic switch disposed in a closed receptacle the combination of a number of contact members, means for connecting said contact members mechanically, a number of connecting terminals attached to the base of the receptacle and means for connecting said contact members and said terminals mechanically and electrically.
3. In a thermostatic switch disposed in a closed glass receptacle the combination of two contact arms, means for connecting said contact arms mechanically comprising an insulating connecting piece and a pin adapted to hold the parts together, two connecting terminals sealed in the base of the receptacle and means for connecting said contact arms and terminals mechanically and electrically.
4. In a thermostatic switch disposed in a closed glass receptacle the combination of two contact arms, means for connecting said contact arms mechanically, two connecting terminals sealed in the base of the receptacle and means for connecting said contact arms and terminals mechanically and electrically comprising an insulating connecting

piece and a pin adapted to hold the parts together.

5. In a thermostatic switch disposed in a closed glass receptacle the combination of two contact arms, means for connecting said contact arms mechanically comprising an insulating stud, insulating washers and a pin passed through said stud and arranged to clamp the parts together, two connecting terminals sealed in the base of the receptacle and means for connecting said contact arms and terminals mechanically and electrically comprising an insulating stud, insulating washers and a pin passed through said stud and arranged to clamp the parts together.

6. In a thermostatic switch disposed in a closed glass receptacle the combination of two contact arms, a thermostatic stem, means for connecting said contact arms and thermostatic stem mechanically, two connecting terminals sealed in the base of the receptacle and means for connecting said contact arms and terminals mechanically and electrically.

7. A method of manufacturing thermostatic switches consisting in making separately a switch support with connecting terminals attached thereto and a switch composed of a number of contact members mechanically connected together, connecting said switch and support by means of said terminals, inserting the switch in a receptacle, fastening the support to the receptacle, evacuating the receptacle and closing the receptacle hermetically.

8. A method of manufacturing thermostatic switches consisting in making separately a switch support with connecting terminals attached thereto and a switch composed of a number of contact members mechanically connected together, connecting said switch and support by means of said terminals, inserting the switch in a receptacle, fastening the support to the receptacle, filling the receptacle with inert gas and closing the receptacle hermetically.

9. A method of manufacturing thermostatic switches consisting in making separately a switch support of glass with terminal plates sealed therein and a switch composed of two contact arms clamped together by means of an insulating stud and a connecting pin passed through the stud, connecting said switch and support by clamping said contact arms and terminals together, inserting the switch in a glass receptacle, sealing the support onto one end of the receptacle, evacuating the receptacle and closing the receptacle hermetically at the other end.

10. A method of manufacturing thermostatic switches consisting in making separately a switch support of glass with terminal plates sealed therein and a switch

composed of two contact arms clamped together by means of an insulating stud and a connecting pin passed through the stud, connecting said switch and support by clamping said contact arms and terminals together, inserting the switch in a glass receptacle, sealing the support onto one end of the receptacle, filling the receptacle with

inert gas and closing the receptacle hermetically at the other end. 10

In testimony whereof I affix my signature in presence of two witnesses.

AXEL OSVALD APPELBERG.
